CLAIM

The ornamental design for a corner bracket, as shown and described.

DESCRIPTION

FIG. 1 is a front perspective view of an inside corner bracket illustrating one embodiment of the invention;

FIG. 2 is a top plan view thereof;

FIG. 3 is a bottom view thereof;

FIG. 4 is a left side elevational view thereof;

FIG. 5 is a right side elevational view thereof;

FIG. 6 is a rear perspective view thereof;

FIG. 7 is a front perspective view of a second embodiment of the design shown in FIG. 1;

FIG. 8 is a top plan view thereof;

FIG. 9 is a bottom view thereof;

FIG. 10 is a left side elevational view thereof;

FIG. 11 is a right side elevational view thereof;

FIG. 12 is a rear perspective view thereof;

FIG. 13 is a front perspective view of a third embodiment of the design shown in FIG. 1;

FIG. 14 is a top plan view thereof;

FIG. 15 is a bottom plan view thereof;

FIG. 16 is a left side elevational view thereof;

FIG. 17 is a right side elevational view thereof; and,

FIG. 18 is a rear perspective view thereof.

FIG. 1.FIG. 2.FIG. 3.FIG. 4.FIG. 5.FIG. 6.

FIG. 7.FIG. 8.FIG. 9.FIG. 10.FIG. 11.FIG. 12.
